MEANS FOR HANDLING FREIGHT

Einar W. Erickson, Port Townsend, Wash.

Application May 16, 1939, Serial No. 273,948

1 Claim. (Cl. 294—67)

This invention relates to the handling of freight, for example, bales, rolls of paper, small crates, and the like, where it is desirable to handle a number of similar bales, rolls or crates at a time.

A particular application of this invention is its use in reference to the handling of rolls or bales of paper in connection with the transferring of these from storage in the mills or warehouses to the holds of ships for transportation purposes.

Various methods and means have been employed heretofore for such purpose, in view of the desirability of handling a number of rolls or bales at a time in order to speed up the loading operation, but such methods and means have in general encountered certain difficulties, such as danger of injury of the edges of paper in the rolls or bales, or have involved extra expense and inconvenience in necessitating the use of auxiliary crates, containers, or platforms for transporting the rolls or bales. Furthermore, regulations set up recently by labor unions governing the loading of such freight into vessels have also imposed restrictions on old methods of handling cargo of this nature.

The object of this invention, in general, is to provide a more efficient method of handling and loading freight of this and similar types to enable such difficulties as those indicated above to be avoided.

A further object of this invention is to provide simple and inexpensive means for carrying out such improved method.

These and incidental objects I attain by providing an improved "pallet board" or storage and transfer platform together with an improved "cargo sling" and associated means, to be described, and by employing these in the manner to be explained in the following description, in which reference is made to the accompanying drawings.

In the drawings:

Fig. 1 is an isometric view of my improved "pallet board," which is employed as the preferred means for carrying out my method, the "pallet board" here being shown with a quantity of rolls of paper (these being indicated in broken line) stacked thereon as during transfer or storage;

Fig. 2 is a corresponding end elevation of the "pallet board;"

Fig. 3 is an isometric view of my "pallet board" and of my improved "cargo sling" illustrating the use of the two in combination; and

Fig. 4 is a view further illustrating the carrying out of my method and showing the manner in

which the load is handled when being deposited by the "cargo sling" prior to the releasing of the sling.

Referring first to Figs. 1 and 2, my "pallet board" comprises a rigid platform-like structure consisting of any suitable base 10, a slotted floor or deck 11, and supporting sills 12, 12; and may be conveniently built up of wooden planks and timbers in the form shown. The base 10 preferably has a plane bottom so as to enable it to rest on stacks of goods in a warehouse, and the sills 12, 12 are made sufficiently thick to permit the entrance of the elevating prongs of an end lift or tiering truck between the base 10 and deck 11 when the "pallet board" is to be moved about with its load stacked thereon.

The deck 11 is formed of side pieces 13 and 14 and a center plank (or group of planks) 15. These members are preferably of greater length than the base members to provide an overhang 20 along two edges as shown, and these members are so spaced as to form two symmetrically arranged and equal-sized spaces 16 and 17 in the deck extending in the direction shown.

In practical use, the goods to be stored and subsequently shipped, such as the rolls of paper illustrated, are stacked on the deck 11 of the "pallet board." These "pallet boards" with their loads can then be moved from place to place or piled one upon the other in the storage warehouse by end lift trucks in the usual manner. The slots 16 and 17 in the deck of the "pallet board" are made to accommodate a movable floor board which constitutes the bottom member 18 (see Figs. 1, 2 and 3) of my "cargo sling." This bottom member 18 of the "cargo sling" is made substantially the same length as the deck boards 13, 14 and 15 of the "pallet board" and is adapted, by suitable reduction in width and thickness, to be slidingly inserted in the slots 16 and 17 in the "pallet board" and thus rest on the sills 12, 12 directly beneath the rolls of paper or other goods piled on one-half of the "pallet board."

In addition to the bottom board 18 the "cargo sling" comprises a load-top engaging member or top board 19 and means for drawing the two boards toward each other so as to securely clamp the load between them. The top board 19 is of practically the same proportions as the bottom board 18. At opposite corners of the top board 45 anchorages for the ends of the ropes 22 and 23 are formed as at 20 and 21. The ropes 22 and 23 extend downwardly from these anchorages and pass around sheaves of the fall blocks 24 and 25 and then extend upwardly thru enlarged aper-

tures 26 and 27 in the top board 19 to the auxiliary rings 28 and 29. The auxiliary rings 28 and 29 are connected to the main ring 30 at the top of the "cargo sling" by short ropes 31 and 32. 5 Chains 33 and 34 are securely attached at the bottom of the fall blocks 24 and 25 and carry hooks 35 and 36, respectively, at their lower ends, substantially as shown in Fig. 3. These hooks are adapted to engage metal bales 37 or any other 10 suitable fixtures, firmly disposed in the slotted ends of the bottom board 18.

The "cargo sling" is connected to a hook 38 (see Figs. 3 and 4) of the usual hoisting line 39, for example, the hoisting line of a ship's winch, 15 by means of either the main ring 30 or the auxiliary rings 28 and 29. The main ring 30 is used for loads of normal height and the auxiliary rings 28 and 29 may be used for lower loads. In the latter case the two rings 28 and 29 are brought 20 together at the hook 38 and the main ring 30 is allowed to hang free. In either case an effective grip is obtained between the top and bottom boards 19 and 18.

When the "cargo sling" is empty, the top and 25 bottom boards are prevented from being drawn unnecessarily close together by the buttons or stops 40 and 41 which are firmly secured in the proper position on the ropes 22 and 23 between the sheaves of the blocks 24 and 25 and the apertures 26 and 27 of the top board, and thus, as 30 these portions of the ropes are pulled upwardly, the buttons 40 and 41 will come into contact with the top board 19 and effectively prevent further movement of the bottom board and top board 35 towards each other.

When the rolls of paper, or other goods, piled 40 on the "pallet board" are to be loaded, for example, into the hold of a vessel for transportation, I move the "pallet board" with the rolls or goods thereon in the usual manner by means of an end lift truck or similar device to the ship's side on the wharf. The "cargo sling," which is attached to the hoisting line 39 of the ship, is then lowered over the "pallet board" and the hooks 45 35 and 36 are detached to permit the load-supportable floor on bottom board 18 to be inserted in the deck space 16 under the rolls of paper or goods stacked directly above. Then the hooks 35 and 36 are reattached and the load located 50 above the bottom board 18 is ready to be lifted. As the ship's hoist line is pulled upward, the top board 19 of the "cargo sling" will be drawn downwardly and the bottom board 18 drawn upwardly until these boards press tightly on the top and 55 bottom of the interposed load. However, since only the flat top and bottom boards engage the load, there will be no danger during this portion of the operation of damaging the load. This is an important feature. Furthermore, the load 60 cannot become dislodged and fall out of the "cargo sling" during the transfer of the load from the "pallet board" to the ship as long as there is a pull on the hoisting line. As the pull on the hoisting line continues, thru the operation of 65 the ship's winch, the sling and interposed load are raised as shown in Fig. 3. The load is lifted clear of the ship's side, swung up over the hold and then lowered so as to land in the hold.

Fig. 4 illustrates the manner in which I prefer

70 to deposit the load in the ship's hold. A mat 42, made to serve as a cushion, is laid in the hold and the "cargo sling" lowered so that the load rests on this mat. Continued lowering of the "cargo sling" permits the load to assume the inclined position shown in Fig. 4 and finally to come to rest on its side. During all this time, however, the clamping action of the sling retains the rolls of paper or other articles constituting the load in position until they have been brought 10 to rest on the mat as mentioned. Slackening of the hoist line will now permit one of the hooks 35 or 36 to be disconnected, or will permit the top and bottom portions 19 and 18 to be slid 15 up off of the load entirely, thus completely releasing the "cargo sling" from the load. The rolls of paper or other articles can then, if desired, be moved into other parts of the ship's hold. Meanwhile, the "cargo sling" is returned to the dock and the other half of the "pallet board" 20 load is transferred to the ship's hold in the same manner. The entire load carried on the "pallet board" may, however, be removed at one time, if desired, by using two "cargo slings" coupled to 25 the same hoisting line. When my method and means are to be employed for unloading cargo from a ship's hold, the reverse order is followed. Thus the number of rolls or bales, for example, which it is desired to handle at a time are placed 30 together, the bottom and top portions of my "cargo sling" are placed in position around the same, the sling is tightened, and lifted with its load. The load is pulled up out of the ship's hold and deposited on the "pallet board" on the 35 wharf, the bottom board 18 being brought down into one of the slots 16 or 17 of the "pallet board"; the "cargo sling" is loosened, the bottom board is slid out from under the load, and the sling is returned to the ship's hold to repeat 40 the operation.

Various modifications might be made in both my "cargo sling" and in the "pallet board" used in carrying out my method, without departing from the principle of my invention. These means which I have shown I have found to be 45 very satisfactory, and the form and construction of both "cargo sling" and "pallet board" illustrated in the attached drawings I regard as the preferred form. It is not my intention, however, to limit my invention otherwise than as set forth 50 in the claim.

I claim:

A loading platform, comprising side base bars, a plurality of spaced main bars connecting the side base bars and secured thereto, one or more supplemental bars adapted to be interposed in the space or spaces between the main bars and supported on the side base bars or removed therefrom at will, the thickness of the supplemental bars being less than the thickness of the adjacent main bars to facilitate positioning the supplemental bars under a load on the platform or removal of said supplemental bars from under a load, the supplemental bar or bars forming part of the platform when loading, and means at opposite ends of each supplemental bar for attachment of sling mechanism to lift the load from the platform.

EINAR W. ERICKSON.
